UNITED STATES PATENT OFFICE

GEORGE H. PERKINS, OF WELLESLEY, MASSACHUSETTS, ASSIGNOR TO POWDRELL & ALEXANDER, INC., OF BOSTON, MASSACHUSETTS, A CORPORATION OF MASSACHUSETTS

DESIGN FOR A TEXTILE FABRIC

Application filed August 17, 1929. Serial No. 32,430. Term of patent 3½ years.

To all whom it may concern:

Be it known that I, GEORGE H. PERKINS, a citizen of the United States of America, residing in Wellesley, in the county of Norfolk and Commonwealth of Massachusetts, have invented a new, original, and ornamental Design for Textile Fabric, of which the following is a specification, reference being had to the accompanying drawing, forming part thereof.

Figure 1 is a diagrammatic showing of the

decoration contained between the stripes, and Figure 2 is an enlarged detail showing of the specific design illustrated diagrammatically in Figure 1.

I claim:

The ornamental design for a textile fabric as shown and described.

Signed by me at Boston, in the county of Suffolk and Commonwealth of Massachusetts, this 3rd day of July, 1929.

GEORGE H. PERKINS.
